PAPER-FEEDING MACHINE.

No. 836,164.

Specification of Letters Patent.

Patented Nov. 20, 1906.

Application filed August 28, 1905. Serial No. 276,044.

To all whom it may concern:

Be it known that I, GEORGE R. WILLIAMS, a citizen of the United States, residing at New York, county of Kings, and State of New York, have invented certain new and useful Improvements in Paper-Feeding Machines, fully described and represented in the following specification and the accompanying drawings, forming a part of the same.

10 This invention relates to certain improvements in sheet-feeding mechanism of the character employed in feeding and registering a plurality of sheets which are advanced side by side.

15 Two-sheet-feeding mechanisms have heretofore been employed in which the two sheets were brought into register by first separating the sheets by moving them outward and then moving them inward against guides or 20 stops which acted upon inner edges of the sheets. While the machines referred to are satisfactory for certain classes of work, they are not efficient for certain other classes—as, for instance, work of the character known as 25 “work and turn”—that is, for feeding sheets which are first printed on one side and then turned over and printed or perfected on the opposite side—the impressions from the forms on one side of the sheet lying directly opposite 30 to or “backing up” the impressions of the forms printing on the other side of the sheet, the forms which produce the backing-up impression being arranged on the same side of the machine as the forms which produce the 35 first impression.

Pressmen in feeding presses position their front and side edge guides so as to bring the impressions of the forms the proper distance from the head and one side edge of the sheets, 40 and in successive printings these guides must always coöperate with the head and the same side edge, for if not the impression on one side of the sheet may not be exactly opposite the impression on the other side and the margins may not be alike.

45 In the two-sheet-feeding machines before referred to, such machines being well illustrated in Patent No. 714,847, granted December 2, 1902, the two sheets were registered by being 50 first moved outward and then inward against stops or guides which operate in connection with the inner edges of the sheets to determine the position of the sheets. When work-

and-turn work is to be printed, however, it will be seen that in feeding two sheets in the manner in which they are fed in the machine referred to what were the inner edges of the sheets as the sheets passed through the feeding mechanism for the first printing become the outer edges of the sheets as the sheets pass 60 through the feeding mechanism for the second printing. Inasmuch, however, as the machine referred to is only adapted to register by the inner edges, no matter whether the sheets have been first printed or not, it could 65 not be efficiently used for work-and-turn work, for the reason that the mechanism for registering was not adapted to operate for the second printing on the same edge of the sheet that it operated on for the first printing. 70

It is one of the objects of this invention to produce an improved feeding mechanism for feeding a plurality of sheets side by side which shall embody positioning devices which may operate to position sheets either 75 from the inner or the outer edge.

A further object of the invention is to improve the details of construction of feeding mechanisms of the character referred to.

With these and other objects not specifically referred to in view the invention consists in certain constructions and in certain parts, improvements, and combinations, as will be hereinafter fully described and then specifically pointed out. 80

Referring to the drawings, Figure 1 illustrates in side elevation one embodiment of the improved feeding mechanism. Fig. 2 is a plan view of the construction shown in Fig. 1. Fig. 3 is a detail sectional view on the line 3 3 of Fig. 2, this figure illustrating more particularly the sheet-separating mechanism. Figs. 4 and 5 are detail views illustrating the construction of the sheet-spreading mechanism and the front stop mechanism employed 95 in connection therewith. Fig. 6 is an enlarged detail view illustrating the construction of certain sheet-positioning devices employed. Fig. 7 is a side elevation of the construction shown in Fig. 6. Fig. 8 is an enlarged plan view of one of the positioning devices employed. Fig. 9 is a section on the line 9 9 of Fig. 8. Fig. 10 is a section on the line 10 10 of Fig. 8. Fig. 11 is a section on the line 11 11 of Fig. 10. Fig. 12 is a section on the line 12 12 of Fig. 8, certain parts being 100 105

removed. Fig. 13 is an enlarged plan view of the construction shown at the right-hand end of Fig. 6, the parts being in a different position. Fig. 14 is a section on the line 14 5 14 of Fig. 13. Fig. 15 is a section on the line 15 15 of Fig. 13. Fig. 16 is a section on the line 16 16 of Fig. 13. Fig. 17 is an enlarged side elevation of one of the inner sheet-positioning devices shown at the extreme left in 10 Fig. 2. Fig. 18 is a section on the line 18 18 of Fig. 17. Fig. 19 is a detail sectional view illustrating the construction of the guide and certain devices connected therewith, which are shown at the extreme left of Fig. 2.

15 The feeding mechanism which forms the subject of the present invention is designed to be used in connection with automatic devices for loosening and removing sheets from piles, these devices including, as is well 20 known, buckling devices and sheet-pushers. These devices, however, form no part of the present invention and are not illustrated.

In the particular construction selected to illustrate the invention parts of the side 25 frames which sustain the sheet loosening and pushing devices are indicated at 1, the sheets being advanced by these devices to a pair of forwarding-rolls, one of which is indicated at 2, these rolls being journaled in the frames 1. 30 From these rolls the sheets are forwarded in the particular mechanism shown in the manner to be hereinafter described to the printing mechanism, the cylinder of an ordinary flat-bed printing-machine being indicated at 3. In the particular construction selected 35 to illustrate the invention two side bars are employed, these bars being marked 4 and being pivoted at 5 to arms or extensions 6, which extend forward from the side frames 1. The 40 extensions 6 may be provided with standards or feet 7, which rest upon the feed-board of the machine, which is indicated at 8. The pivoting of the frames 4 in the manner described enables the apparatus to be swung up 45 out of the way when desired. The forward ends of these bars 4 carry castings 9, which may also be supplied with feet 10, these feet resting on the feed-board.

The sheets are forwarded in the particular 50 construction illustrated by tapes which pass around the roll 2, one of these tapes being indicated at 11 in Fig. 1. The upper runs of the tapes pass over rolls 12 13, as usual in such construction, these rolls being idle rolls 55 and being journaled in bearings 14, supported on the bars 4. From the roll 13 the upper runs of the tapes pass around a roll 15, journaled in the castings 9. From this roll the tapes run back to the roll 2, a suitable idle 60 roll or rolls being employed in connection with the under run of the tapes, if necessary. One of these idle rolls is illustrated at 16. Tapes such as have been described are ordinarily employed in feeding mechanism of the 65 character to which the invention relates and

form an efficient sheet-forwarding means. Other suitable means may, however, be employed instead of them, if desired.

Constructions embodying the invention are designed to be used in connection with sheet-feeders which forward a plurality of sheets side by side—that is to say, feeding mechanisms in which a plurality of sheets are simultaneously removed from adjacent piles, the sheets being forwarded side by side 75 by the forwarding mechanism to the printing-machine.

In the best constructions embodying the invention and in order to insure accurate register the sheets as they pass along the 80 forwarding mechanism will first be subjected to the operation of sheet-spreading devices, the purpose of which is to separate or space apart the two sheets. While this sheet-spreading mechanism may be varied in its 85 construction, in the particular machine shown two rods 17 18 are provided, each of these rods being provided with a member or members which operate on the edges of the sheets to separate them. As shown, the rod 90 17 is provided with two such members, these members being marked 19 and 20. In the construction shown the member 19 is formed integrally with the rod and the member 20 is adjustable on the rod by means of a collar 95 and set-screw, (indicated at 21.) Similarly the rod 18 is provided with two members 22 23, the member 22 being integral with the rod and the member 23 being adjustably mounted thereon by means of a collar and 100 set-screw, (indicated at 24.)

The means employed for supporting and operating the sheet-separating means will, of course, vary with the particular construction of members employed. In the particular construction shown the rod 17 is supported at one end by a pin 25, this pin being mounted in an arm 25', carried on a collar 26, which is in turn supported by a rod 27. The end of the arm 25' opposite that which carries the rod may be extended, as shown, and bear against a shaft 28, which will be hereinafter referred to, the end of the arm being formed with a half-round 29, which serves as a guide. The rod 27 and the shaft 28 are carried in 115 brackets 30, these brackets being supported on the side bars 4. The other end of the rod 17 is in the particular construction shown supported by causing it to pass loosely through an eye in a bracket 31, extending upward from one side bar 4. The rod 18 is in the particular construction shown supported in a manner similar to that in which the rod 17 is supported—that is to say, one end of the rod is carried by a pin 32, mounted 120 on an arm 32', fast on a collar 33, this collar being supported on the rod 27, and the extension of the arm 32 is formed with a half-round 34, which bears against the shaft 28. The other end of the rod 18 passes through an 130

eye in a bracket 35, extending upward from the other side bar 4.

In the particular construction shown the spreading members are positively moved in one direction, and, as shown, two rods 36 are employed for this purpose, one of these rods 36 being connected to the collar 33 and the other rod to the collar 26. These rods pass through perforations in ears 37, formed on blocks 38, which are supported on the rod 27, before referred to. These blocks 38 also support guide-posts carrying wheels 39, around which run chains 40, secured to connecting-rods 41, pivoted to levers 42, which are mounted on a cross-rod 43, supported in side frames 1. These levers 42 are cam-levers and are actuated by means of cams 44, mounted on a cam-shaft 45, journaled in the frames 1 and driven by suitable gearing, part of which is indicated in Fig. 2. The rods 36 carry collars 46, and between these collars and the ears 37 are located springs 47. It is to be understood that by this construction the collars 26 33 and the levers 25' 32' are given a reciprocating movement, this movement moving the rods 17 18 sidewise, actuating the spreading members and spreading the sheets.

As any two sheets are forwarded by the tapes, it will be observed that one sheet will pass between the members 20 and 22 of the spreader and the other sheet will pass between the members 19 and 23. These sets of members—namely, 19 23 and 20 22—operate together to position the sheets, the members 19 22 ordinarily first striking the sheets and pushing them away from the center of the sheet-path and the members 20 23 preventing the sheets from being thrown too far by the members 19 22 or returning them if they are thrown too far.

Sheet-spreaders have been heretofore employed consisting of a pair of members which operated to shift the sheets in their passage through the machine. These spreaders, however, comprised pivoted members, and therefore when operated necessarily moved in the arcs of circles. These spreaders have a tendency to swing or twist sheets slightly, making the subsequent registering operations more difficult. The spreaders which have been illustrated and described are advantageous as compared with such a construction, in that their movement is a movement in a right line across the sheet-pathway, so that there is no tendency to swing or twist the sheets. Further, these spreaders make it possible to vary the travel of the sheets with respect to the center of the sheet-pathway. Thus by disconnecting either the rod 17 or the rod 18 from the operating mechanism, which can be readily done, both sheets can be shifted sidewise with respect to the central line dividing the sheet-pathway. Further, the members 20 and 23 may be dis-

connected from the rods 17 and 18, if desired, and both sheets can be shifted sidewise away from the central line dividing the sheet-pathway.

In the best constructions the sheets when 70 being acted upon by the spreading members will rest against front stops. These front stops are or may be constructed as is usual. As shown, these front stops embody under guides 48, which are supported by a cross-rod 49, in turn supported by the standards which form part of the brackets 30. These under guides are located just below the tapes. Above these under guides are located upper guides 50, carried by pins 51, 80 mounted on the supports 52, secured to the rod 27. (See Fig. 4.) The outer ends of these upper guides are shown as recessed, and through these recesses work stops 53, which are carried by supports 54, fast on the shaft 85 28. The shaft 28 is a rock-shaft and is operated from a connecting-rod 55, which is secured to an arm 56, fast on the shaft, and to a cam-lever 57, pivoted on the rod 43. This cam-lever 57 is operated from a cam 58 on 90 the shaft 45, before referred to. In the operation of the mechanism the sheets will be forwarded until they strike the front stops 53, after which the spreading devices operate. The stops are then rocked upward to 95 permit the sheets to be forwarded by the tapes.

After the sheets have been operated upon by the spreading devices, assuming that such spreading devices are employed, they pass 100 onward within the range of action of sheet-positioning devices. These sheet-positioning devices may be variously constructed and may be operated in various ways. Furthermore, the number of these positioning 105 devices employed to act on each sheet may be varied. In the particular construction shown, however, two pairs of these positioning devices will be provided for each sheet.

In the particular construction shown (see 110 Figs. 1, 2, 6, and 13) the rods 4 carry castings 59, these castings being formed to provide collars 60, which embrace the rods, so that the castings are adjustable thereon, the castings being held in position by means of set-screws or in any other suitable manner. These castings serve to support ways 61, which extend across the machine, these ways forming a guide. The castings are also formed to provide pairs of short guides consisting of ribs 62, which support operating blocks or slides 63, which will be hereinafter referred to, there being one of these blocks or slides on each side of the machine. The ways 61 support plates 64, there being one of these plates on each side of the machine. These plates 64 may be adjusted to any desired position in the machine and when so adjusted may be held in position by clamp-screws 65, these screws passing through the 130

plates 64, taking under ribs on the ways 61 and being held in position by wing-nuts 66. These plates 64 are formed to provide ways 67, and in these ways are mounted slides 68, 5 the slides being held in the ways by means of tension-springs 69, as illustrated in Fig. 16. The slides 68 support hollow standards 70, (see Figs. 2, 13, and 15,) which surround sleeves 71, screwed into the slides 68, the 10 standards being held firmly in position by nuts 72 engaging long bolts 73, which pass through the sleeves 71, these bolts being tapped at their lower ends into collars 74, which surround rods 76. The plates 64 are 15 secured to the collars 74 by tongues 75, which depend from the plates and engage reduced portions of the collars. (See Figs. 10 and 15.) The rods 76 pass into and are secured to ears 77 on the slides 63. The 20 interior construction of the standards 70 and the means by which the sides are secured to the rods 76 are similar to the construction illustrated in Figs. 9 and 10, these figures, however, illustrating certain of the other positioning devices which have not yet been described.

The standards 70 support guards 78, (see Figs. 6, 7, and 15,) the function of which is to prevent the ends or edges of the sheets from 25 curling up and to insure that the sheets are acted upon by the devices which will be described. These guards 78 are so located with respect to the slides 68 as to leave narrow openings 79, (see Fig. 7,) into which the 30 edges of the sheets to be positioned enter. These openings with respect to the particular positioning devices now being described face inwardly—that is, toward the center of the sheet-path—and therefore serve to receive 35 the outside edges of the two sheets being advanced along the sheet-path. The standards 70 also support swinging fingers 80, which are fast on short rock-shafts 81, journaled in the standards. (See Fig. 15.) These 40 shafts also carry (see Figs. 7 and 15) arms 82, on which are mounted balance-nuts 83, which are so adjusted as to make it possible for the fingers 80 to be displaced by the 45 resistance of the sheets if the movement of the 50 sheets is obstructed. The lower ends of these fingers 80 lie just behind the openings 79, into which, as has been described, the 55 edges of the sheets enter.

The positioning devices so far described 60 are the exterior positioning devices which the sheets first meet in their travel toward the press—that is, these positioning devices operate upon the exterior edges of the two sheets traveling down the sheet-path. Co-65 operating with these two exterior positioning devices are two interior positioning devices. (See Figs. 2 and 6 to 10.) The right-hand one (see Fig. 6) of these interior devices is mounted on a slide 84, which moves in the ways

61, and the left-hand one is mounted on a 65 slide 85, which also moves in the ways 61. Each of these devices includes in the machine illustrated a standard 70, a sleeve 71, a nut 72, a guard 78, a long bolt 73, a swinging finger 80, a shaft 81, an arm 82, and a balance-70 nut 83. These parts are arranged to operate in the same manner that they do in connection with the exterior positioning devices so far described. The guard 78, which co-operates with the slide 84, is arranged so that the 75 opening 79 faces toward the right-hand exterior positioning device, and the guard 78, which co-operates with the slide 85, is arranged so that the opening 79 faces toward the left-hand exterior positioning device. 80

It has been heretofore stated that each of the slides 63 has a rod 76 secured to it. The rod 76, extending inwardly from the right-hand slide, extends under the interior positioning devices and is secured to a spring 86, 85 the end of this spring being secured to a pin 87 on one of the ways 61. Similarly the rod 76, which extends inwardly from the left-hand slide 63, passes under the interior positioning devices and is secured to a similar 90 spring 86, this spring being also secured to a pin 87 on the other way 61. While the mechanism for moving these positioning devices may be widely varied, in the particular construction shown the slides 63 are included in 95 this mechanism. These slides 63 are each provided with pins 88, to which are connected chains 89, these chains running around wheels 89', connected to rods 90, (see Fig. 1,) which run along the outside of the bars 4, the 100 connection being effected by means of adjustable collars 91. The rods 90 are fast to arms 92 on short rock-shafts 93, these shafts being journaled in brackets which form a part of the standards 7. These rock-shafts 105 93 have operating-arms 94, which are connected by links 95 to cam-levers 96, pivoted on the shaft 43, before referred to, and operated by cams 97 on the cam-shaft 45. By this construction the rods 76 are moved in 110 one direction by the cams and connections described and in the opposite direction by the springs.

The bolts 73 of the several positioning devices may be operated so as to either lock or 115 release these positioning devices from the rods. When the sheets are being registered by their interior edges, the right and left hand exterior positioning devices will be secured to the operating-rods 76 and the interior positioning devices will be disconnected from the rods and held stationary. When the construction is operating in this manner, the sheets will be pushed by the exterior guides inward against the interior guides, 120 these operating simply as stops. When it is desired to register the sheets by the outer edges, the interior positioning devices will be 125

made fast to the rods 76 and the exterior positioning devices will be held stationary and act simply as stops.

Another arrangement of the mechanism is possible by which one sheet will be registered by the inner edge and the other by the outer edge. For instance, the right-hand exterior positioning device may be held stationary and the right-hand interior positioning device secured to its operating-rod. The left-hand interior positioning device may be held stationary and the left-hand exterior positioning device secured to its operating-rod. With this arrangement the left-hand sheet will be pushed by the left-hand exterior positioning device against the left-hand interior positioning device, which will act as a stop. The right-hand sheet will be pushed by the right-hand interior positioning device against the right-hand exterior positioning device, acting as a stop. With this arrangement the left-hand sheet will be registered by its inner edge and the right-hand sheet will be registered by its outer edge.

Any suitable construction may be employed for holding the several positioning devices stationary when desired. In the particular construction shown each of the interior positioning devices is provided with a bracket-arm 98, extending from a plate 99, which is secured to the under side of the slides 84 85, as shown in Fig. 9, by means of a bolt 100 or in any other suitable manner. The plate 99 in this construction is also utilized to hold the slides 84 85 in position on the ways 61. The arms 98 have perforations through them, and through these perforations pass rods 101, these rods being supported in brackets 102, secured to the ways 61. The arms 98 may be secured to the rods 101 in any suitable manner—as, for instance, by set-screws 103. In order to provide for accurate adjustment of the interior devices, the outer ends of each of the rods 101 may be threaded and a nut 104 may be used to adjust the rod, this nut lying, as shown, between two parts of the bracket 102, and therefore held stationary, so that when it is turned the rod will be moved in one direction or the other. Jam-nuts 105 may be provided to hold the rods in adjusted position.

In order to hold the exterior positioning devices stationary when desired, two latches 106 are employed, in the particular construction illustrated these latches being pivoted on the plates 64 and taking over keepers 107, fast on the slides 68. In the particular construction illustrated the ends of these latches when they are in operative position lie behind the swinging fingers 80 of these exterior positioning devices and prevent any movement of these fingers.

In order to lock the swinging fingers 80 of the interior positioning devices when they are held stationary, swinging plates 108 are

provided, these plates being mounted on the threaded sleeves 71 and held in position by the nuts 72. The hubs of the balance-arms 82 are squared, as indicated in Fig. 7 and better shown in the enlarged view, Fig. 17, and when the plates are swung around over them the fingers 80 are locked against movement, as will be readily understood.

If desired, a sheet-guard consisting of an angle-plate 109 may be secured to the upper way 61 to prevent the front ends of the sheets from striking against the side of the way.

While in some instances a single pair of positioning devices for each sheet may be employed, in the best constructions two pairs of such devices will be employed for each sheet, and such constructions are illustrated in the drawings. When additional pairs of positioning devices are employed, they may be in all essential respects substantially similar to those heretofore described. In the particular construction illustrated the castings 9 support a guard-plate 110. (See Figs. 2 and 18.) This guard-plate supports a way or guide 111, there being a coöperating way or guide 112, which is supported by the castings 9. Slide-blocks 113 are employed, these blocks being generally similar to the slide 63, before described, although being somewhat different in outline. These slide-blocks are connected by chains 114 to the rods 90, before described, and they have extending from them rods 76, connected to springs 86, this construction being similar to the construction already described.

The exterior positioning devices are mounted on slides 68 and may be in construction and operation precisely similar to the exterior positioning devices heretofore described. The interior positioning devices are mounted on slides 115, which while they operate like the slides 84 85 are somewhat different in configuration. These slides are well shown in Fig. 18, from which it appears that the guide 112 is formed with a guide-rail top which fits into a recess 116 on the under side of the slides 115. Secured to these slides 115 are perforated blocks 117, which effect the same function as the arms 98 in the construction before described—that is, they connect the slides to adjusting-rods 118. These adjusting-rods are connected by cross-bars 119 to micrometer-screw adjusting devices 120, similar in operation to the devices before described, although the brackets 121 are slightly different in form from the brackets 102.

The interior and exterior positioning devices are the same in construction and operation as those which have been previously described and can be connected to and disconnected from the operating mechanism in the same manner, so as to act either as pushers or stops, as the case may be.

In order to bridge the space between the

guides or rails which carry the lower set of adjusting devices, under guides 122 are employed, these being fingers of spring metal of usual construction. These guides are shown 5 as mounted on sliding blocks 123, which engage in ways in the guides 111, tension-springs 124 being employed to keep the blocks 123 snug in the ways. These fingers form no part of the invention, and any other suitable 10 construction may be substituted therefor. The fingers 122 coöperate with front stops 125 of a construction commonly used in connection with flat-bed printing-machines.

Changes and variations may be made in 15 the construction by which the invention is carried into effect. The invention is not, therefore, to be limited to the specific construction hereinbefore described, and illustrated in the accompanying drawings.

20 What is claimed is—

1. In a sheet-feeding mechanism, the combination with means for forwarding two sheets side by side, of means for bringing the sheets into feeding register, said means including devices for shifting the sheets sidewise, and means whereby said devices may be caused to operate to shift each sheet inwardly or outwardly.

2. In a sheet-feeding mechanism, the combination with means for forwarding two sheets side by side, of sheet-spreading devices, means for bringing the sheets into feeding register, said means including devices for shifting the sheets sidewise, and means 35 whereby said devices may be caused to operate to shift each sheet inwardly or outwardly.

3. In a sheet-feeding mechanism, the combination with means for forwarding two sheets side by side, of means for bringing the sheets into feeding register, said means including positioning devices which operate on the sides of the sheets, and means whereby said devices are caused to operate either as sheet shifters or stops.

4. In a sheet-feeding mechanism, the combination with means for forwarding two sheets side by side, of sheet-spreading devices, means for bringing the sheets into feeding register, said means including positioning 50 devices which operate on the sides of the sheets, and means whereby said devices are caused to operate either as sheet shifters or stops.

5. In a sheet-feeding mechanism, the combination with means for forwarding two sheets side by side, of interior positioning devices for each sheet, exterior positioning devices for each sheet, and means whereby either the interior or the exterior positioning 60 devices may be caused to shift the sheets sidewise.

6. In a sheet-feeding mechanism, the combination with means for forwarding two sheets side by side, of interior positioning devices for each sheet, exterior positioning de-

70 vices for each sheet, and means whereby the exterior positioning devices may be caused to shift the sheets sidewise and the interior positioning devices may be caused to act as stops, or the interior positioning devices may be caused to shift the sheets sidewise and the exterior devices may be caused to act as stops.

7. In a sheet-feeding mechanism, the combination with means for forwarding two sheets side by side, of sheet-spreading devices, interior positioning devices for each sheet, exterior positioning devices for each sheet, and means whereby either the interior or the exterior positioning devices may be caused to shift the sheets sidewise.

8. In a sheet-feeding mechanism, the combination with means for forwarding two sheets side by side, of sheet-spreading devices, interior positioning devices for each sheet, exterior positioning devices for each sheet, and means whereby the exterior positioning devices may be caused to shift the sheets sidewise and the interior positioning devices may be caused to act as stops, or the interior positioning devices may be caused to shift the sheets sidewise and the exterior devices may be caused to act as stops.

9. In a sheet-feeding mechanism, the combination with means for forwarding two sheets side by side, of two interior positioning devices for each sheet, two exterior positioning devices for each sheet, and means whereby either the interior or the exterior devices may be given a sidewise movement to shift the sheets.

10. In a sheet-feeding mechanism, the combination with means for forwarding two sheets side by side, of sheet-spreading devices, two interior positioning devices for each sheet, two exterior positioning devices for each sheet, and means whereby either the interior or the exterior devices may be given a sidewise movement to shift the sheets.

11. In a sheet-feeding mechanism, the combination with means for forwarding two sheets side by side, of two interior positioning devices for each sheet, two exterior positioning devices for each sheet, means whereby either the two interior or the two exterior devices may be given a sidewise movement to shift the sheet, and means for holding the devices not moved stationary to act as stops.

12. In a sheet-feeding mechanism, the combination with means for forwarding two sheets side by side, of sheet-spreading devices, two interior positioning devices for each sheet, two exterior positioning devices for each sheet, means whereby either the two interior or the two exterior devices may be given a sidewise movement to shift the sheet, and means for holding the devices not moved stationary to act as stops.

13. In a sheet-feeding mechanism, the combination with means for forwarding two sheets side by side, of front stops, sheet-

spreaders, means for giving the spreaders a right-line movement at right angles to the path of travel of the sheets and registering means operating on the sheets acted upon by the spreaders.

14. In a sheet-feeding mechanism, the combination with means for forwarding two sheets side by side, of front stops, and a sheet-spreader comprising a set of members 10 operating on the outer and inner edges of one sheet and a set of members operating on the outer and inner edges of the other sheet.

15. In a sheet-feeding mechanism, the combination with means for forwarding two sheets side by side, of front stops, a sheet-spreader comprising a set of members operating on the outer and inner edges of one sheet and a set of members operating on the outer and inner edges of the other sheet, and 20 means for adjusting one member of each set.

16. In a sheet-feeding mechanism, the combination with means for forwarding two sheets side by side, of front stops, a sheet-spreader comprising a set of members operating on the outer and inner edges of one sheet and a set of members operating on the outer and inner edges of the other sheet, and means for adjusting the members which 25 operate on the outer edges of the sheets.

30 17. In a sheet-feeding mechanism, the combination with means for forwarding two sheets side by side, of front stops, a sheet-spreader including members operating on the inner edges of the sheets, and means for giving said members a right-line movement at right angles to the paths of movements of the sheets.

40 18. In a sheet-feeding mechanism, the combination with means for forwarding two sheets side by side, of front stops, a sheet-spreader including members operating on the outer edges of the sheets, and means for giving said members a right-line movement at right angles to the pathway of the sheets.

45 19. In a sheet-feeding mechanism, the combination with a plurality of outer-sheet-shifting devices, of a plurality of inner-sheet-shifting devices, operating mechanism, and means for connecting any or all of said shifting devices to the operating mechanism.

50 20. In a sheet-feeding mechanism, the combination with means for forwarding two sheets side by side, of a pair of sheet-shifting devices, one member of the pair being located alongside the path of the inner edge of one sheet and the other member of the pair being located alongside the path of the outer edge of said sheet, a second pair of sheet-shifting devices, one member of said pair being located alongside the path of the inner edge of the other sheet and the other member of the pair being located alongside the path of the outer edge of said other sheet, an operating mechanism, and means for connecting

55 a member of each pair of sheet-shifting devices to the operating mechanism.

21. In a sheet-feeding mechanism, the combination with means for forwarding two sheets side by side, of a pair of sheet-shifting devices, one member of the pair being located alongside the path of the inner edge of one sheet and the other member of the pair being located alongside the path of the outer edge of said sheet, a second pair of sheet-shifting devices, one member of said pair being located alongside the path of the inner edge of the other sheet and the other member of the pair being located alongside the path of the outer edge of said other sheet, an operating mechanism, means for connecting a member 70 of each pair to the operating mechanism, and means for holding the other member of each pair stationary whereby said members may 75 act as stops.

22. In a sheet-feeding mechanism, the combination with means for forwarding two sheets side by side, of guiding means angularly disposed with relation to the sheet-path, a pair of sheet-shifting devices mounted in said guiding means, one member of said pair 80 lying alongside the path of the inner and the other member of the pair lying alongside the path of the outer edge of one sheet, a second pair of sheet-shifting devices mounted in said guiding means, one member of said pair lying 85 alongside the path of the inner and the other member of said pair lying alongside the path of the outer edge of the other sheet, and means for giving a member of each pair a 90 sidewise movement to shift the sheets. 95

100 23. In a sheet-feeding mechanism, the combination with means for forwarding two sheets side by side, of guiding means angularly disposed with relation to the sheet-path, a pair of sheet-shifting devices mounted in said guiding means, one member of said pair 105 lying alongside the path of the inner and the other member of the pair lying alongside the path of the outer edge of one sheet, a second pair of sheet-shifting devices mounted in said guiding means, one member of said pair lying 110 alongside the path of the inner and the other member of said pair lying alongside the path of the outer edge of the other sheet, means for giving a member of each pair a sidewise 115 movement to shift the sheets, and means for holding the other member of each pair stationary to act as sheet-stops.

120 24. In a sheet-feeding mechanism, the combination with means for forwarding two sheets side by side, of a guide, a pair of positioning devices mounted on the guide, one member of said pair lying alongside the path of the inner edge of one sheet and the other member lying alongside the path of the outer edge of said sheet, a second pair of positioning devices mounted on the guide, one member of said pair lying alongside the path of 125

the inner edge and the other member lying alongside the path of the outer edge of the other sheet, an operating mechanism for moving the positioning devices along the 5 guide, and means for connecting either the outer members of said pairs or the inner members of said pairs to the operating mechanism.

25. In a sheet-feeding mechanism, the 10 combination with means for forwarding two sheets side by side, of a guide, a pair of positioning devices mounted on the guide, one member of said pair lying alongside the path of the inner edge of one sheet and the other 15 member lying alongside the path of the outer edge of said sheet, a second pair of positioning devices mounted on the guide, one member of said pair lying alongside the path of the inner edge and the other member lying 20 alongside the path of the outer edge of the other sheet, an operating mechanism for moving the positioning devices along the guide, means for connecting either the outer members of said pairs or the inner members 25 of said pairs to the operating mechanism, and means for holding the other members of the pairs stationary to act as stops.

26. In a sheet-forwarding mechanism, the 30 combination with means for forwarding two sheets side by side, of two inner-sheet pushers, two outer-sheet pushers, an operating mechanism, and means for connecting either the inner or outer pushers to the operating mechanism.

35 27. In a sheet-forwarding mechanism, the combination with means for forwarding two sheets side by side, of two inner-sheet pushers, two outer-sheet pushers, an operating mechanism, means for connecting either the inner 40 or outer pushers to the operating mechanism, and means for holding the pushers not connected to the operating mechanism stationary so as to cause them to act as sheet stops.

45 28. In a sheet-feeding mechanism, the combination with means for forwarding two sheets side by side, of two pairs of positioning devices, one member of each pair lying alongside the path of the outer edge of one 50 sheet and the other member of each pair lying alongside the path of the inner edge of the same sheet, two other pairs of positioning devices, one member of each pair lying alongside the path of the inner edge of the 55 other sheet and the other member of each pair lying alongside the path of the outer edge of said other sheet, an operating mechanism, and means for connecting either the outer or

inner members of said pairs to the operating mechanism. 60

29. In a sheet-feeding mechanism, the combination with means for forwarding two sheets side by side, of two pairs of positioning devices, one member of each pair lying alongside the path of the outer edge of one sheet 65 and the other member of each pair lying alongside the path of the inner edge of the same sheet, two other pairs of positioning devices, one member of each pair lying alongside the path of the inner edge of the other sheet and the other member of each pair lying alongside the path of the outer edge of said other sheet, an operating mechanism, means for connecting either the outer or inner members of said pairs to the 70 operating mechanism, and means for holding the other members of the pairs stationary to act as sheet-stops. 75

30. In a sheet-feeding mechanism, the combination with means for forwarding two sheets side by side, of two pairs of pushers, one pusher of each pair lying alongside the path of the outer edge of a sheet and the other pusher of each pair lying alongside the path of the inner edge of said sheet, two 80 other pairs of pushers, one pusher of each pair lying alongside the path of the inner edge of the other sheet and the other pusher of each pair lying alongside the path of the outer edge of said sheet, operating means, 85 and means for connecting either the outer or the inner pushers to the operating mechanism.

31. In a sheet-feeding mechanism, the combination with means for forwarding two sheets side by side, of two pairs of pushers, one pusher of each pair lying alongside the path of the outer edge of a sheet and the other pusher of each pair lying alongside the path of the inner edge of said sheet, two 90 other pairs of pushers, one pusher of each pair lying alongside the path of the inner edge of the other sheet and the other pusher of each pair lying alongside the path of the outer edge of said sheet, operating means, 95 and means for connecting either the outer or the inner pushers to the operating mechanism, 100 and means for holding the unconnected pushers stationary to serve as sheet-stops. 105

In testimony whereof I have hereunto set 110 my hand in the presence of two subscribing witnesses.

GEORGE R. WILLIAMS. [L. S.]

Witnesses:

PATRICK BRENNAN,
FRANK E. BLACKBURN.
